UNITED STATES PATENT OFFICE.

THOMAS COOK, OF STALEYBRIDGE, AND GECRGE DURRANT, OF MANCHESTER,
ENGLAND.

APPARATUS FOR GUIDING FABRICS INTO STENTERING-MACHINES.

1,132,562.

Specification of Letters Patent. Patented Mar. 23, 1915.

Application filed June 8, 1914. Serial No. 843,775.

To all whom it may concern:

Be it known that we, THOMAS COOK and GEORGE DURRANT, subjects of the King of Great Britain and Ireland, and residents, respectively, of Staleybridge, in the county of Chester, and Higher Openshaw, Manchester, in the county of Lancaster, England, have invented certain new and useful Improvements in Apparatus for Guiding Fabrics into Stentering-Machines, of which the following is a specification.

Our invention relates to improvements in apparatus for guiding fabrics into stentering or like machines and while applicable 15 for use in connection with guiding arrangements in general is particularly adapted for employment in connection with the automatic guiding apparatus forming the subject of an application for patent Serial No. 20 784842 filed August 14th 1913 made by George Durrant, one of the present applicants, the object of the present invention being to provide preliminary guiding means for the cloth passing into the stentering or 25 like machine and particularly to such types of stentering machine as are provided with what is known as a "swissing" motion.

Where motions of the type referred to are employed the cloth, while generally moving 30 forward by being attached to the stenter chains at each side of the machine, is momentarily retarded at one side or selvage and advanced at the other side, alternatively, so causing the weft of the fabric to assume a 35 position varying from a line at right angles to the sides to a line at an inclination thereto. This action is known as "swissing" and as a result that portion of the fabric which is entering on to the stenter chains is alter- 40 natively slack at one side and tight at the other. To accommodate this action the cloth is usually passed over guide rollers arranged at the front end of the stentering or like machine, such rollers usually being of a coni- 45 cal type so that the tendency of the selvages of the fabric is to rise toward the higher parts of the cones and so keep the fabric stretched somewhat transversely. Further, the cones are adapted to partially accommo- 50 date themselves to the tension or lack of tension on the cloth, but the arrangements hitherto employed for this purpose have been somewhat defective so that the necessary accommodating action does not prop- 55 erly take place.

Our invention is designed with the object of providing improved means for supporting the conical or other guiding rollers and consists essentially in mounting each of such rollers on a link parallel motion adapted to 60 allow it to accommodate itself freely to the tension of the fabric.

Our invention will be fully described with reference to the accompanying drawing which indicates one form of parallel motion 65 we adopt in carrying it out.

The aforesaid drawing comprises in Figure 1 a side elevation of so much of a stentering machine as is necessary to show the application of our invention thereto and 70 Fig. 2 plan of same.

In carrying out our invention we mount each conical roller *a* on a spindle *b* which is fixed to an arm *c*. The arm *c* has a socket *d* which is mounted on an arm or bar *e*, the ends of which are pivoted to links *f* which project in opposite directions and which are normally arranged parallel to each other. The other ends of the links *f* are pivoted to a supporting bracket *g*, so that the spindle *b* 80 and the roller *a* are constrained to oscillate in a straight line. This straight line is arranged in a suitable position with respect to the cloth under tension, and when the tension of the cloth is reduced the roller *a* is 85 pressed against the cloth by a spring *h* connected to the bracket *g* and to one of the links *f*.

With mechanism of the type described it is impossible for the rollers to stick as is 90 sometimes the case when they are mounted on slides. We do not confine ourselves to any particular detail construction of link parallel motion so long as the objects we have in view are attained.

In conjunction with arranging each roller on a parallel motion device we mount it on suitable bearings *i*, usually ball bearings, supported by the central spindle *b*, the inner end of which is pivoted to a bracket *j* fixed 100 on the arm *c* of the link motion, such spindle being so arranged that it can be turned about the vertical pivotal center *k* and then be locked in position at any suitable angle. The locking may conveniently be effected by 105 forming an arm *m* on the spindle *b* carrying a bolt *n* passing through a slot *o* in the bracket *j*. We do not, however, confine ourselves to this particular detail arrangement as it will be obvious adjustment can be 110

readily carried out in other ways. The roller spindle bracket *j* is likewise mounted on an arm *c* of the link motion so that the spindle *b* may be raised and lowered at its 5 free end as required to place the cone or roller in any suitable position. As shown in the drawings this adjustment may be effected by a set screw *p*. By the aforesaid means adjustment of the roller is provided 10 for in all directions required.

In some cases a cylindrical roller may be employed in place of a conical one, the flexibility of the cloth permitting it.

What we claim as our invention and desire 15 to secure by Letters Patent is:—

1. The combination, with a stationary support, of two links having their opposite ends pivoted to the support and normally arranged parallel to each other, a bar having 20 its ends pivoted to the adjacent ends of the said links, a spindle mounted on the middle portion of the bar, a roller journaled

on the said spindle, and means for moving the roller in a straight line in one direction.

2. The combination, with a stationary 25 support, of two links having their opposite ends pivoted to the support and normally arranged parallel to each other, a bar having its ends pivoted to the adjacent ends of the 30 said links, a socket secured on the said bar, a spindle pivotally connected to the socket and provided with means for securing it to the socket after its angular position has been adjusted, a roller journaled on the said spindle, and means for moving the roller 35 in a straight line in one direction.

In testimony whereof we have hereunto set our hands in the presence of two witnesses.

THOMAS COOK.
GEORGE DURRANT.
